ABSTRACT OF THE DISCLOSURE

A single coil telephone ringer wherein the coil has a permanent magnet core with pole pieces projecting beyond the ends of the coil. A U-shaped armature is pivoted about half way along the length of the coil. The cooperating pole pieces and armature ends are angled to enhance the magnetic moment. The volume of the ring is controlled using a formed wheel arrangement for clamping the bell hammer.

This invention relates to a polarised magnetic device, such as a ringer, as used in a telephone subscriber's instrument.

According to the present invention there is provided a polarised magnetic device, which comprises a magnetisable core surrounded by an energising coil, end portions of said core projecting out of said coil, an armature of generally U-shaped construction mounted so that the base portion of the U is generally parallel to said core, said armature being rockable about a pivoted axis between the ends of said base portion, end portions of the legs of said U-shaped portion which co-operate with the end portions of said core, and a source of magnetic flux which imparts magnetisation of the same sense to the faces of the end portions of the core which co-operate with the end portions of said armature, so that energisation of the coil with alternating current causes said armature to rock about its pivots, the end portions of the armature and the faces of the pole ends of said core which co-operate with said armature end portions being at an angle to the length of said core.

An embodiment of the invention will now be described with reference to the accompanying drawings, in which:

FIG. 1 is a side view of a ringer according to the invention.

FIG. 2 is a plan view of the ringer of FIG. 1, the arrow I indicating the direction from which it is seen in FIG. 1.

FIG. 3 is a section of the armature pivot of the ringer of FIG. 1.

FIG. 4 shows the arrangement of the armature securing spring.

FIG. 5 is a side view and a cross-section of an alternative form of volume control wheel.

FIG. 6 is an alternative form of ringer frame to that of FIG. 1.

Referring first to FIGS. 1 and 2, the ringer includes a coil-carrying spool 1 on a ferrite magnet 2, polarised to have one longitudinal face a north pole and the other longitudinal face a south pole. The alternating current through the coil therefore sets up magnetic fields which alternately reinforce or diminish the field of the permanent magnet in an opposite manner at each pole. There is also a soft iron core 3. It should be noted that the ringer has one coil only, which simplifies construction. An armature 4 is pivoted at 5, 6 on a platform 7 provided by an upstanding portion of a base plate 8. The pivots may, for example, be ball bearings or rollers held captive in re-

2

cesses in the armature and the platform, as shown in FIG. 3. Alternatively each pivot can be a ridge on the inside of the armature which engages with an indentation on the platform or vice versa. Again, domeheaded rivets on the platform or the armature and held captive in recesses on the armature or platform respectively could be used. The pivots are held in place (where they are balls or rollers) and the armature retained in position by a formed clip spring 9 bearing against the outer surface of the armature 4. A central portion of the spring passes through a hole in the armature 4 and is held in a cruciform slot and recess in the platform 7, as shown in FIG. 4.

As can be seen from FIG. 4, the slot is larger in the longitudinal than in the vertical sense. The spring is mounted by pushing its right hand end (FIG. 4) through the longer slot and then turning it through 90° so that it reaches the position shown in FIG. 4. This, with the cut-away portions in the thickness of the portion 7 ensures that the spring positively retains the armature; hence it will not "wobble" as wear occurs in use.

When the coil is energised by an alternating current, the core 11 is magnetised, and its magnetisation direction is reversed on every half cycle. The armature whose ends thus alternate in polarity between north and south 25 polarisation co-operates with the steady polarity flux from the permanent magnet, such that the armature rocks about its pivot, the rocking occurring in a plane perpendicular to the axis through the pivots. The flux of the permanent magnet tends to bias the armature by acting to polarize the armature. The magnetic bias causes the armature to react faster to the alternating current generated flux. The end portions 10, 11 (FIG. 2) of the armature and of the core are angled so that the direction of the magnetic force acting on each end pole face of the armature is perpendicular to the line from the pivot to that end. Hence the force has a maximum moment about the pivot. The armature is shown as having its pole ends sharply angled, but if this is inconvenient, for example for production reasons, it would be possible for the junction between the end portion and the legs of the armature to be curved.

Referring again to FIGS. 1 and 2, a hammer 12 is carried by the armature, and when the armature rocks, the hammer strikes two gongs (not shown), one on each side of the hammer head.

The volume of sound emitted by the bell can be controlled by a wheel 13 mounted beneath the hammer so that the arm of the hammer floats in a channel around the circumference of the wheel. This channel has a variable width, as shown in FIG. 2, and rotation of the wheel 50 causes the walls of the channel to converge or diverge from the arm, controlling the distance the arm of the hammer can move sideways, and hence the force with which it hits the gongs. The arm of the hammer is, of course, flexible.

An alternative form of volume control wheel is shown in FIG. 5. This wheel is an eccentric and its circumferential channel is lined with a damping material such as a foam rubber or plastics material. Rotation of the wheel when mounted beneath the arm of the hammer causes the foam rubber lining mentioned above to bear on the arm. This exerts a damping action on the arm, lessening the force with which the head of the hammer strikes the gongs.

In FIG. 1 the volume control wheel is shown axially supported between two bent-up portions of the base plate. Another method of supporting the wheel is shown in FIG. 6, where a composite moulding provides an axial support. The plastics wheel with an integral axle is pressed into the cylindrical bearings. The walls of the bearings move apart allowing entry and finally snap inwards, partially embracing and securing the axle. This method of

insertion of the axle is shown in the inset to FIG. 6. During adjustment of the volume control, an upward force is exerted on the axle which tends to push it out of its bearings. The axle remains secured, however, as the moulding is screwed firmly to the base plate, thus preventing the walls from flexing outwards.

Reverting to FIG. 2, the spool unit is secured to its base plate by two screws 14 (FIG. 2) which enter slots 15 at the sides of the spool cheeks and engage in two threaded holes in the base plate. Adjustment of the airgaps is made by slackening off these screws and sliding the spool together with the magnet and core towards or away from the armature. Slots are also provided on the spool unit in the alternative construction of FIG. 6, as indicated at 15'.

It is to be understood that the foregoing description of specific examples of this invention is made by way of example only and is not to be considered as a limitation on its scope.

What we claim is:

1. A polarized magnetic ringing device having at least one gong, said device comprising a magnetizable core surrounded by an energizing coil, end portions of said core projecting out of said coil to form pole pieces, an armature of generally U-shaped construction with the base portion of the U-shape normally parallel to said core, said armature being rockable about a pivotal axis located between the ends of said base portion, end portions of the legs of said U-shaped armature cooperatively associated with the pole pieces, arm and hammer means attached to said armature in a position normal to the length of said core and juxtaposed with said hammer to said gong, permanent magnet means for imparting magnetization of the same sense to the faces of each of the pole pieces, so that energization of the coil with alternating current causes the said armature to rock about the pivotal axis, and the end portions of the armature and the faces of the pole pieces being parallel to each other and at an obtuse angle to the length of the core.

2. A polarised magnetic device as claimed in claim 1, wherein said armature ends and pole pieces lie respectively along and parallel to the line from said pivotal axis to the ends of the armature.

3. A device as claimed in claim 2, and in which said pivotal axis is about which the armature rocks is defined by a plurality of balls or rollers, each of which is held captive in recesses in said armature and in a support therefor.

4. A device as claimed in claim 2, and in which said pivoted axis about which the armature rocks is defined by ridges on the armature located in indentations in a support for the armature, or vice versa.

5. A device as claimed in claim 4, wherein said armature is held in place by a formed clip spring bearing against the opposite surface of the armature from that on which the pivots lie.

6. The ringing device as claimed in claim 5 including means for securing said formed clip spring, said securing means comprising a cruciform slot and recess in the base of said ringing device, abutment means in said armature lying directly over said slot, whereby a central portion of 10 said spring passes through said abutment and is secured in a said cruciform slot and recess.

7. A device as claimed in claim 1 wherein arm means for carrying a hammer are attached to said armature and wherein control means mounted beneath the arm of the hammer comprise rotatable means to adjust the force with which the hammer strikes the gong and hence the volume of the sound emitted.

8. A device as claimed in claim 7, in which said control means is a wheel having a circumferential channel of 20 varying width in which the arm of the hammer floats, rotation of said wheel causing the walls of the channel to converge on or diverge from the arm, whereby the distance travelled by the arm and hence the force with which the hammer strikes the gong or gongs is controllable.

9. A device as claimed in claim 7, in which said control means is an eccentric wheel having a circumferential channel lined with a damping material such as foam rubber, rotation of said wheel causing the lining to bear on 30 the arm of the hammer, whereby a damping force is applied thereto which reduces the force with which the hammer strikes the gong.
